UNITED STATES PATENT OFFICE

107,995

DESIGN FOR A RADIO CABINET

Archie L. Herron, Chicago, Ill., assignor to Stewart-Warner Corporation, Chicago, Ill., a corporation of Virginia

Application February 19, 1937, Serial No. 67,745

Term of patent 7 years

To all whom it may concern:

Be it known that I, Archie L. Herron, a citizen of the United States, residing in the city of Chicago, county of Cook, and State of Illinois, have invented a new, original, and ornamental Design for a Radio Cabinet, of which the following is a specification, reference being had to the accompanying drawing, forming a part thereof.

In the drawing:

Figure 1 is a perspective view showing the

front and one side of a radio cabinet embodying my new design.

Figure 2 is a top plan view of the same.

Characteristic features of the design are shown in full lines in the drawing, the remainder of the outline being shown in broken lines.

I claim:

The ornamental design for a radio cabinet, substantially as shown and described.

ARCHIE L. HERRON.
